SLUDGE PUMPING APPARATUS

Fred W. Hartstein, Brooklyn, N. Y.

Application May 20, 1944, Serial No. 536,471

8 Claims. (Cl. 103—5)

This invention relates to improvements in an apparatus and method of sludge pumping and has for its primary object the pumping of viscous oils and sludges to a relatively great height and over relatively long distances. Whereas the invention may be adaptable for other purposes, the same is primarily intended for the sludge cleaning of the fuel tanks of an oil burning maritime vessel.

With the advent of oil as a fuel the ship operator was confronted with the problem of periodically cleaning the fuel tanks. The bunker oils, which are distillate products when gasoline is extracted from natural oils, have an asphalt base which in the length of time precipitates out of the oil and forms a heavy gluish sludge which does not respond to conventional pumping methods. When the sludge accumulation becomes so extensive that it seriously encroaches on the storage capacity of the pumpable fuel oil in the tank, the tank has, of course, to be cleaned out in order to make room for the useful fuel.

Also when bottom repairs are required in the fuel tanks, and as such repairs invariably require hot work like riveting and welding, the sludges as well as the gases must be removed so that the work may be undertaken without danger of explosion.

I am aware that others, such as Wheeler in his Patents Nos. 1,405,173 and 1,480,482, have employed vacuum pumping for removing sludge from the fuel tanks of a ship, but in such instances the sludge is pumped from the fuel tank to one of a pair of tanks mounted on the deck of a cleaning barge, while the other of the tanks is emptying its sludge contents into the storage space of the cleaning barge. This shift-over from one vacuum tank to another requires frequent lapses in the pumping operation, for the capacity of the vacuum tanks is limited. Also, pumping is suspended during the period of time that it requires for the vacuum tanks to reestablish the high vacuum required to operate such system.

It is therefore one of the important features of my invention to expedite the pumping of sludge from the fuel oil tanks of a ship, by providing vacuum depository tanks in the hull of a cleaning barge into which the sludge is directly sucked by means of a high vacuum pump.

Prior sludge pumping apparatus and methods including Wheeler, have admitted air and steam at the inlet end of the system to emulsify the viscous material to be pumped so as to increase its temperature and accordingly decrease its viscosity and thus prevent clogging of the pump-

ing apparatus and system. It is therefore a further feature of my invention to utilize the chilling water-swept hull surface of a cleaning barge as a steam condenser for rapidly condensing such saturated steam as may enter the tank of the barge during a pumping operation. By constantly maintaining a relatively low gas and vapor pressure in the sludge receiving tank, the work performed by the vacuum pump is considerably reduced.

From the aforesaid features, it is apparent that the basis of my invention consists in the use of chilled water-swept hull of a cleaning barge as a vacuum tank into which sludge is directly sucked by a high vacuum pump to increase the pumping rate over previous apparatus and methods with which I am familiar. However, other novel features of the invention will become apparent as the following specification is read in conjunction with the accompanying drawing, in which,

Figure 1 is a diagrammatic cross sectional view through an oil burning vessel and an attendant sludge cleaning barge.

Figure 2 is an enlarged detail vertical sectional view through the intake nozzle with a part broken away in section.

Referring to the drawing by reference characters, the numeral 10 designates my improved sludge cleaning barge in its entirety which includes a rigid metal hull 11 preferably constructed of steel. The top of the hull 11 is closed by a deck plate 12. Preferably the hull 11 is divided by transverse partitions 13 into a plurality of vacuum tanks or sludge receiving compartments 14. The barge 10 is shown as being buoyantly supported upon the surface of a body of water 15, whereupon the bottom and opposite sides of the metal hull 11 are disposed in heat exchange relation to the body of water 15. Thus three surfaces of each vacuum tank 14 are subjected to the chilling temperature of the body of water 15 on which the barge 10 floats.

Mounted on the deck 12 is a conventional vacuum pump 16 having a suction inlet pipe 17 leading to each vacuum tank 13. Each vacuum tank 13 has a pipe riser 18 extending upwardly from the deck, said pipe riser having communication with its related vacuum tank and constituting the sludge inlet thereto.

In Figure 1 of the drawing, the cleaning barge 10 is shown as being moored beside a fuel oil burning ship 19, the hull of which is provided with the usual double bottom 20 within which the fuel oil sludge to be pumped accumulates.

A transmission hose 21 has one of its ends connected to the pipe riser by a coupling 22, while the other end of said hose extends upward over the side of the ship 19 and downward through hatches or other passageways into the space between the double bottom 20. The free end of the hose 21 carries an inlet nozzle 23 in the form of a pipe reducer provided with air inlets 24 inwardly from the inlet end thereof. A steam nozzle 25 extends through and into the nozzle 23 to which a steam hose 26 is connected, the latter receiving its supply of steam from an attendant tugboat or from the steam supply of the ship 19. The steam nozzle enters the hose nozzle between the air inlets 24 and the outer end thereof as best illustrated in Figure 2. In use the inlet end of the nozzle 23 is submerged into the sludge 27 with the air inlets above the level thereof to enable air to be drawn into the transmission hose 21 along with the sludge to agitate or crack the gluish sludge material entering the nozzle 23 to effect an emulsion or mechanical dilution essential to its transfer. Steam is also added to the flow of emulsified viscous material through the steam nozzle 25 to increase the temperature of the same and decreasing its viscosity to prevent the sludge from clinging to the side of the suction hose 21, which otherwise would eventually clog the same.

In operation of my apparatus and system, the pump 16 is placed in operation which creates a relatively high vacuum in one of the selected vacuum tanks 14, whereupon the sludge 27 is sucked through the nozzle 23 into the hose 21, along with a proportionate amount of air drawn through the inlets 24 and steam from the steam nozzle 25. The high vacuum sucks the material into the tank 14 where it accumulates until the tank is filled, after which the hose 21 is connected to the riser of the next tank to receive a load. As the heated sludge enters the tank 14, the bulk of the saturated steam vapor accompanying the same is immediately chilled by reason of the fact that it is subjected to the chilling effect of the surrounding water with which three sides of the vacuum tank are in constant heat exchange relation. This chilling action causes an immediate condensing of the vapors, which thereupon reduces the combined gas and vapor pressure within the vacuum tank 14. It is therefore obvious that the work to be performed by the vacuum pump 16 is considerably reduced with the reduction of the combined gas and vapor pressure, thus the pumping rate of the sludge is greatly increased.

From the foregoing it will be understood that by reason of the heat exchange relation of the water with the bottom and sides of the vacuum tank, I am able to considerably reduce the temperature thereof over those systems in which the vacuum tanks are mounted in an exposed position upon the deck of the cleaning barge, which accordingly reduces the vapor pressure within the vacuum tank 13 and increases the working efficiency of the vacuum pump 16.

It is a known fact that air pressures vary with the absolute temperature of the air. In my apparatus and system such air within the vacuum tank is maintained at a relatively low temperature due to the cooling action of the water which is in heat exchange relation to three surfaces of the vacuum tank. Thus, in comparing my apparatus and system with others employing a vacuum pump of like air pumping

capacity, it follows that the air in my apparatus and system is more dense than that which is being withdrawn in the other systems with which I am familiar. Thus, as the carrying capacity of the air varies directly as to its density, it is apparent that the pumping capacity of my apparatus and system is greater than that of other comparable sludge pumping apparatus and systems.

10 By constantly maintaining the tank or compartment free of accumulated gases, the likelihood of fire and explosion is minimized.

While I have shown and described what I consider to be the preferred embodiment of my invention, I wish it to be understood that such changes in construction, materials, design, and uses as come within the scope of the appended claims may be resorted to if desired without departing from the spirit of my invention.

Having thus described the invention, what I claim as new and desire to secure by Letters Patent is:

1. In an apparatus for pumping viscous sludges from the inside of a ship, a barge, a vacuum compartment within said barge having heat conducting walls disposed below the water line of said barge, a flexible transmission line having an outlet end connected to said vacuum compartment and its inlet end disposed in the viscous sludge to be pumped, means for allowing atmospheric air to enter the transmission line, means for injecting steam into the transmission line, and means on said barge for creating a relatively high vacuum in the vacuum compartment.

2. In an apparatus for pumping viscous sludges from the inside of a ship, a barge buoyantly supported by a body of water, a vacuum compartment within said barge having metal heat conducting walls disposed below the surface level of the body of water in heat exchange relation to the body of water, a transmission line having an outlet end connected to the vacuum compartment and an inlet end adapted to be led to the inside of a ship and disposed in the viscous sludge to be pumped, means for allowing air to enter the transmission line at the inlet end thereof, means for injecting steam into the transmission line at the inlet end thereof, and a high vacuum pump mounted on the deck of said barge having its inlet connected to said vacuum compartment for withdrawing a relatively great volume of air therefrom and thereby creating a relatively high vacuum therein.

3. In an apparatus for pumping viscous sludge from the inside of a ship, a barge buoyantly supported by a body of water, a sludge receiving compartment within said barge having metal heat conducting walls disposed below the surface level of the body of water in heat exchange relation to the body of water, a flexible transmission hose having an outlet end connected to said sludge receiving compartment and an inlet end adapted to be led to the inside of a ship and disposed in the viscous sludge to be pumped, means for admitting air at the inlet end of said hose and a high vacuum pump mounted on the deck of said barge having its inlet connected to the sludge receiving compartment for withdrawing a relatively great volume of air therefrom and thereby creating a relatively high vacuum therein.

4. In an apparatus for pumping viscous sludge from ships, a buoyant sludge receiving tank having metal walls disposed in direct heat exchange relation to the surface of a body of water upon which it floats, a sludge transmission hose hav-

ing its outlet end connected to the tank and an inlet end immersed in the sludge to be pumped, means for admitting air at the inlet end of said hose, and means carried by said barge for creating and maintaining a relatively high vacuum in the sludge receiving tank.

5. In an apparatus for pumping viscous sludges from the inside of a ship, a hollow barge, the interior of said barge constituting a vacuum sludge-receiving compartment, a transmission line having an outlet end connected to said vacuum compartment and an inlet end adapted to be disposed in the sludge to be pumped, means at the inlet end of the transmission line for admitting atmospheric air therein, and means on the barge for creating a vacuum in the vacuum compartment.

6. In an apparatus for pumping viscous sludges from the inside of a ship, a hollow barge adapted to be moored adjacent the ship to be pumped having a portion disposed below its water line for the cooling of the interior thereof below atmospheric temperature by the surrounding water on which it floats, the interior of said barge constituting a vacuum sludge-receiving compartment, a transmission line having an outlet end connected to said vacuum compartment and an inlet end adapted to be disposed in the sludge to be pumped, means at the inlet end of the transmission line for admitting atmospheric air therein, and a vacuum pump mounted on the

barge exteriorly of the vacuum compartment and having its inlet connected to said vacuum compartment and its outlet exhausting to the atmosphere.

5. In an apparatus for pumping watery viscous sludges from the inside of a ship into an overside buoyant receptacle comprising a transmission line communicating with said receptacle, means for introducing air into the inlet end of said transmission line, means for sucking sludge and sludge material to be pumped through the transmission line by withdrawing air from the receptacle to create a vacuum therein, the liquid in which the said receptacle floats acting to chill the exterior of the receptacle thus increasing the vacuum therein.

8. In an apparatus for pumping watery viscous sludges from the inside of a ship into an overside buoyant receptacle comprising a transmission line communicating with said receptacle, means for introducing air into the inlet end of said transmission line, means for introducing steam into the inlet end of said transmission line, means for sucking sludge and sludge material to be pumped through the transmission line by withdrawing air from the receptacle to create a vacuum therein, the liquid in which the said receptacle floats acting to chill the exterior of the receptacle thus increasing the vacuum and condensing the steam therein.
